UNITED STATES PATENT OFFICE.

ISAAC H. CLARK, OF BOSTON, MASSACHUSETTS, ASSIGNOR TO PAUL P. TODD, OF SAME PLACE.

IMPROVEMENT IN CHEMICAL FIRE-ENGINES.

Specification forming part of Letters Patent No. **90,637**, dated June 1, 1869.

To all to whom these presents shall come:

Be it known that I, ISAAC H. CLARK, of Boston, in the county of Suffolk and Commonwealth of Massachusetts, have made an invention of certain Improvements in Chemical Fire-Engines, so called; and do hereby declare the following to be a full, clear, and exact description thereof, due reference being had to the accompanying drawings, making part of this specification, and in which—

Figure 1 is a vertical central and longitudinal section, Fig. 2 a transverse section, and Fig. 3 a horizontal section, of an apparatus in which my invention is embodied. Fig. 4 is a representation of a modification of the invention, to be hereinafter referred to.

This invention relates to a class of fire-engines now coming into general use known as "chemical fire-engines," or those in which various chemical agents, which in themselves or in their gaseous products are destructive to combustion, are employed in combination with the water thrown by such engine to subdue flame either on land or on shipboard, the purpose of the invention being primarily to relieve the pumps of the engine from the corrosive action of the chemical ingredients, and, secondarily, to preserve the ingredients in an inert condition until they come directly in contact with the flames to be extinguished.

The invention consists in constructing the air-chamber of a fire-engine (otherwise of ordinary construction) in such manner that it shall serve the double purpose of an air-chamber and of holding in suspension within it the chemical ingredients to be conveyed therefrom by the water, and in combining with the pumps and the tub of the engine a pipe with two inlet-orifices, one conveying water from the exterior of the engine directly and the other from the interior of the tub, both inlets being regulated by one valve, and operating as hereinafter explained, the discharging-outlet of the air-chamber being combined therewith in any well-known manner.

In the drawings before mentioned as accompanying this specification, and which illustrate my invention, A denotes the body of a tub; B B, the pumps; C, the air-chamber, and C' the discharging-pipe of the latter, such parts being arranged and provided with the

ordinary working beam and brakes, and operating in manner similar to fire-engines now in use.

In carrying out my invention I dispose within the air-chamber C, and preferably at its upper part, a receptacle or means of holding in suspension therein the chemical ingredients or combination of ingredients, such means being in the present instance, and as shown at D in the drawings, a foraminous or gauze basket fixed within the interior of the air-chamber, and, as before premised, at the upper part thereof, a filling-orifice, a, being formed in the upper part of such air-chamber, and communicating with the basket D, for the purpose of allowing the desired substances to be deposited within the latter, the orifice a being provided with a screw-plug, b, for securely closing it.

c in the accompanying drawings represents the suction or feed pipe as extending from the exterior of the engine into and through its tub, and into the base or valve-box of the air-chamber in the usual manner. The pipe c has a branch inlet-pipe, d, applied to or making part of it, such pipe communicating with the interior of the tub of the engine. A cock or valve, e, is situated at the point of intersection, this valve being of such construction as to be capable of opening communication between either of the pipes c and d and the pumps of the engine, and to cut off communication of the other therewith, in order that the water may be supplied to such pump, either from the exterior of the pipe c or from the interior of the tub, by means of the pipe d.

In practical use of the above-described engine, water supplied to the air-chamber C by means of the pumps B B in the ordinary manner, and through one of the pipes c or d, comes in contact with the chemical ingredient contained in such air-chamber, such ingredients or their gaseous products being gradually absorbed by and conveyed with the water issuing from the engine.

I would remark that in place of one gauze or foraminous cylinder or cage for containing the chemical ingredients, as shown in the drawings, two or more may be adopted, in order to hold ingredients of different characters.

The chemicals deposited within the air-

chamber may be of such nature that, though combined, they shall remain in a normal or inert condition until they come in contact with the flames to be subdued, when they shall create and exhale a powerful gas directly upon the flames, by which means nearly the entire amount of combustion-destroying gas is economized which is now lost in transit, the stream of water being the vehicle for precipitating the chemical compound upon the fire.

As the chemical ingredients employed in the above-described engine at no time come in contact with the pumps thereof, the corrosive and destructive action of these chemicals upon the pumps is entirely avoided, which fact constitutes an important advantage in my invention, as it enables me to adapt an ordinary fire-engine, with very little expense, to the purposes before explained.

Various means other than the basket *o* before mentioned may be adopted for confining the chemical material or compound within the air-chamber *c*, without affecting the characteristic feature of my invention, which, as before prefaced, consists in making the air-chamber of a fire-engine the receptacle of chemical agents. For instance, a foraminous or gauze shelf may be placed across the interior of the air-chamber, upon which the chemicals may be deposited; or such shelf may be composed of solid metal, having an orifice made through

it for escape of the chemicals, such orifice being provided with a titillating valve, as shown in Fig. 4 of the accompanying drawings, the ebullition of the inrushing water within the air-chamber producing such vibrations of the stem of the valve as to cause intermittent partial openings of the orifice sufficient to allow of a gradual escape of the chemical substances through such orifice.

Having thus described the nature and operation of what I consider to be my invention, I claim as such invention, and desire to secure by Letters Patent of the United States, as follows:

Claims.

1. Adapting the air-chamber of a fire-engine to the double purpose of an air-chamber and of a receptacle for containing chemical ingredients of such nature as to remain inert until acted upon by the flames upon which they are thrown, for the purpose substantially as before explained.

2. In combination with the air-chamber *C*, adapted as before explained, the pipes *c* and *d*, provided with the valve *e*, and operating as before set forth and explained.

ISAAC H. CLARK.
